(57) **CLAIM**

The ornamental design for a bench seat, as shown and described.

DESCRIPTION

FIG. 1 is a front, right hand side perspective view of a bench seat embodying the principles of my new design;

FIG. 2 is a front view thereof;

FIG. 3 is a rear view thereof;

FIG. 4 is a top view thereof;

FIG. 5 is a bottom view thereof;

FIG. 6 is a side view thereof as seen from the left-hand side of FIG. 2;

FIG. 7 is a side view thereof as seen from the right-hand side of FIG. 2; and,

FIG. 8 is a sectional view taken along a vertical line midway through, and as seen from, the right-hand side of FIG. 2.

The sectional view, FIG. 8, being shown to illustrate the upper features of the bench seat not otherwise discernible from FIG. 7.
